UNITED STATES PATENT OFFICE

104,124

DESIGN FOR AN INCLINOMETER

Annabelle E. Ward, Denver, Colo., assignor of
one-third to William E. Albertson, Daytona
Beach, Fla., and one-third to Tom Botterill,
Denver, Colo.

Application October 16, 1936, Serial No. 65,329

Term of patent 7 years

To all whom it may concern:

Be it known that I, Annabelle E. Ward, a citizen of the United States of America, residing at Denver, in the county of Arapahoe and State of Colorado, have invented a new, original, and ornamental Design for Inclinometers, of which the following is a specification, reference being had to the accompanying drawing, forming part thereof.

The figure is a perspective view of the inclinometer showing my new design.

I claim:

The ornamental design for an inclinometer, as shown.

ANNABELLE E. WARD.
